UNITED STATES PATENT OFFICE.

JEREMIAH VANDERBILT, OF BROOKLYN, NEW YORK, ASSIGNOR TO THE WILL & BAUMER COMPANY, OF SYRACUSE, NEW YORK.

DESIGN FOR A CANDLE-SHADE.

SPECIFICATION forming part of Design No. 27,741, dated October 19, 1897.

Application filed August 23, 1897. Serial No. 649,281. Term of patent 7 years.

To all whom it may concern:

Be it known that I, JEREMIAH VANDERBILT, a citizen of the United States, residing at Brooklyn, county of Kings, and State of New York, have invented and produced a new and original Design for Candle-Shades or the Like, of which the following is a specification.

My invention relates to a design for a candle or lamp shade; and it consists in the configuration and disposition of parts in such a manner as to produce a pleasing effect upon the eye, all of which is substantially illustrated in the accompanying drawings, in which—

15 Figure 1 is a top plan view. Fig. 2 is a side view thereof. Fig. 3 is a vertical sectional elevation, these three views being deemed necessary to properly illustrate my design.

The design consists of a row or series of 20 rows of pear-shaped flowers arranged concentrically upon a frusto-conical base, as shown in the drawings, and a circle of ruffles extending laterally upon the upper portion of the base.

a is the frusto-conical base, upon which the 25 pear-shaped flowers *b* are arranged, and is provided at its upper end with a concaved ring *c*, which serves as a support for the circular ruffle.

e are long petals extending from the heart 30 of the flowers.

f is a fanciful band of ornamental braid or the like secured between the top of the row of flowers and the base.

Having described my invention, what I 35 claim, and desire to secure by Letters Patent, is—

The design for candle-shades or the like, substantially as herein described and shown.

In witness whereof I have hereunto set my 40 hand this 12th day of August, 1897.

JEREMIAH VANDERBILT.

In presence of—

C. H. ECKERMAN,
HUBERT H. WALL.
